UNITED STATES PATENT OFFICE.

LEVI T. STEPHENSON, OF TRINIDAD, COLORADO, ASSIGNOR OF THREE-FOURTHS TO OLA M. JORNDT AND EFFIE L. STEPHENSON, OF KANSAS CITY, KANSAS, AND CORAL G. JORNDT, OF SAN FRANCISCO, CALIFORNIA.

NUT-LOCKING WASHER.

SPECIFICATION forming part of Letters Patent No. 728,323, dated May 19, 1903.

Application filed December 20, 1902. Serial No. 135,990. (No model.)

To all whom it may concern:

Be it known that I, LEVI T. STEPHENSON, a citizen of the United States, residing at Trinidad, in the county of Las Animas and State of Colorado, have invented a new and useful Nut-Locking Washer, of which the following is a specification.

This invention relates to nut-locks of that character which employ a locking-tongue secured to a base or washer and arranged to engage a nut to prevent its turning.

The object is to provide a very simple structure of this character wherein the locking-tongue is housed and protected, being also held against accidental displacement, the means for accomplishing these purposes also serving as a bearing for a tool in moving the tongue to an inoperative position with relation to the nut.

One and the preferred embodiment of the invention is illustrated in the accompanying sheet of drawings, wherein—

Figure 1 is a perspective view of a portion of a rail-joint, showing the lock applied to one of the bolts thereof. Fig. 2 is a vertical transverse sectional view through the same. Fig. 3 is a horizontal longitudinal section taken on the line $\alpha\alpha$ of Fig. 2. Fig. 4 is a perspective view of the lock.

Similar reference-numerals indicate corresponding parts in all the figures of the drawings.

In the embodiment herewith illustrated a base or washer 5 is employed having the usual bolt-receiving opening 6 therethrough. This washer is preferably angular in form and is provided at one edge with a hood formed by an outstanding side wall 7 and an overhanging wall 8. An intermediate portion of the hood is cut away, as shown at 9, and said hood preferably tapers toward one end, as shown more clearly in Fig. 3. Arranged within this hood is a locking-tongue 11, that extends across the cut-out portion, one end of the tongue fitting snugly within the smaller end of the hood and being secured by a rivet 12, that passes through the overhanging wall, the tongue, and the washer. This tongue is formed of spring metal and

its free end bears against the under face of 50 the outer end of the overhanging wall 8. The rear edge of the tongue is arranged contiguous to the outstanding wall 7, while the opposite edge, or at least the portion thereof arranged in the cut-out portion 9 of the hood, 55 is sharpened, as shown at 13.

While the lock may be used upon nuts employed for various purposes, it is herewith shown in connection with a bolt used in rail-joints, said bolt being designated by the reference-numeral 14, passed through the usual fish-plates 15 and the web of the rail 16. The washer is placed upon the threaded end of the nut so that it will rest against the adjacent fish-plate, and the hood is preferably 60 disposed at the upper edge, as shown. A nut 17, of any desirable form, is then screwed upon the bolt, and during its rotation the corners thereof will pass through the cut-out portion of the hood, pressing downwardly 65 upon the locking-tongue, which will spring back to place as each corner passes out of said cut-out portion. Thus the nut will be held against retrograde movement. To release the same it is only necessary to insert 70 a wedge-tool between the overhanging wall and the free end of the tongue, whereupon said tongue will be moved against the base-plate or washer, as indicated in dotted lines in Fig. 3, whereupon the nut may be turned 75 backwardly as will be readily understood.

It will be evident that this lock is very simple, the base or washer and the hood being formed of a single piece of sheet metal and the tongue being readily secured in the manner shown and described. The arrangement of this tongue within the hood is advantageous in several ways. In the first place, it is housed and protected to a great extent from the elements and it cannot be readily 80 struck in an accidental manner. By having the rear edge located contiguous to the outstanding wall and the nut bearing against the front edge it will be evident that said outstanding wall prevents the displacement of 85 the tongue should abnormal strain be brought against it by the accidental retrograde movement of the nut. The overhang-

ing wall also serves as a bearing for the tool in moving the tongue to an inoperative position, and thus three distinct functions are performed by the single hood in connection 5 with the tongue described.

From the foregoing it is thought that the construction, operation, and many advantages of the herein-described invention will be apparent to those skilled in the art with-10 out further description, and it will be understood that various changes in the size, shape, proportion, and minor details of construction may be resorted to without departing from the spirit or sacrificing any of the advantages 15 of the invention.

What I claim, and desire to secure by Letters Patent, is—

1. In a nut-lock, the combination with a washer having a hood overhanging its outer 20 face, of an outwardly-springing tongue secured within the hood and having a portion normally spaced from the washer, said tongue being pressed inwardly toward the washer upon the passage of the nut thereover.

2. In a nut-lock, the combination with a washer having an outstanding sidewall, of a 25 spring locking-tongue secured at one end to the washer, the other end being free and movable toward and from the washer, one of 30 the edges of the tongue being arranged to engage a nut to prevent the same turning, the opposite edge being disposed contiguous to the wall against which it is arranged to bear to prevent lateral displacement of said 35 tongue.

3. In a nut-lock, the combination with a washer having an outstanding hood at one edge, of a spring locking-tongue secured at one end to the washer and arranged within the hood, said tongue being arranged to 40 swing within the hood toward and from the washer.

4. In a nut-lock, the combination with a washer having an outstanding hood at one edge, said hood having an intermediate por-45 tion cut away, and a spring locking-tongue secured in the hood at one side of and ex- tending across the cut-out portion, the por- 50 tion of said tongue extending across the cut-out portion of the hood, being movable to- ward and from the washer to permit a nut moving thereover.

5. In a nut-lock, the combination with a washer having an outstanding hood at one edge that overhangs the washer, said hood 55 having an intermediate portion cut away, a spring locking-tongue arranged within the hood and extending across the cut-away por- 60 tion, said tongue being movable toward and from the washer, and a fastening device pass- ing through the overhanging wall of the hood, the tongue and the washer to secure the tongue in place.

In testimony that I claim the foregoing as my own I have hereto affixed my signature in 65 the presence of two witnesses.

LEVI T. STEPHENSON.
